ALEXANDER McARTHUR, OF SINGER, CLYDEBANK, SCOTLAND, ASSIGNOR TO THE
SINGER MANUFACTURING COMPANY, A CORPORATION OF NEW JERSEY.

HEMMING AND FOLDING ATTACHMENT FOR SEWING-MACHINES.

1,162,181.

Specification of Letters Patent. Patented Nov. 30, 1915.

Application filed February 26, 1914. Serial No. 821,115.

To all whom it may concern:

Be it known that I, ALEXANDER McARTHUR, a subject of the King of the United Kingdom of Great Britain and Ireland, and residing at Singer, Clydebanks, Dumbartonshire, Scotland, have invented certain new and useful Improvements in Hemming and Folding Attachments for Sewing-Machines, of which the following is a specification, reference being had therein to the accompanying drawings.

This invention relates to hemming and folding attachments for sewing machines, and has for its object to provide means adapted to counteract the tendency of the toothed feeding member of the sewing machine to advance the lower ply of a folded structure faster than the upper ply thereof, whereby said structure, a hem for example, is distorted, its plies being drawn "out of line."

The invention comprises a flat tension-spring fixed to the separator-blade of a hemming or folding attachment, its forward end being disposed intermediate said blade and the base of a folding plate upon which rests the body-portion or "lower ply" of the folded fabric. Means are provided for moving the tension-spring into engagement with the lower fabric ply and for varying the pressure of the spring, said means including a controlling-member which moves intermediate the separator-blade and an inclined portion of the tension-spring, and acts as a wedge to force the latter downwardly. The controlling-member is adjustable to increase or decrease its effective action, and said member is moved into engagement with the tension spring by means of a cam-lever, said movement being in opposition to a spring which normally holds the controlling-member in ineffective position.

In the drawings, Figure 1 is a perspective view, partly in section, of a hemming and folding attachment embodying my improvements; and Fig. 2 is a vertical section longitudinally of the same. Fig. 3 is a perspective view from the under face of the attachment.

The improvements are shown applied to a hemming and folding attachment of known form, comprising a supporting-plate A pivotally secured by means of stud-screw 1 to a base-plate 2 adapted to be adjustably se-

cured to the bed-plate of a sewing machine in the usual manner. Undue movement of the supporting plate with its connected parts is prevented by means of a clamping screw 3 secured to the base-plate and provided with a head which overlies the edges of a slot formed in the forward face of the supporting plate. Formed integrally with the supporting plate A is a bridge-piece 4, its outer end being bent downwardly to engage the angular end 5 of an arm 6 projecting laterally of a separator-blade 7. The bridge-piece 4 is provided with a longitudinal slot 4^x to receive a rectangular lug 8 formed transversely of the upper face of an adjustable edge-turning member 9 provided at its forward end with a guide-wall 10 and at its rearward end with a U-shaped edge-turning wall 11. The edge-turning member also supports a smoothing plate 12, the function of which is well known in the art. Opposite to the edge-turning member is the U-shaped folding wall 13^x of a folding-plate 13 formed integrally with supporting plate A and provided with a base portion 14 upon the upper face of which rests the body portion or "lower ply" of the folded fabric. It will be seen that adjustment of the edge-turning member 9 toward or from the folding plate 13 will vary the width of the folded structure, and that the edge-turning member may be secured in its adjusted position by means of the clamping screw 15.

Secured to the under face of the separator-blade 7 is a flat tension-spring 16. The tension-spring is provided with two spaced arms 16^x formed with apertures to receive fastening screws 17 which serve to hold said arms fixed between rectangular washers 18 and the lower face of separator-blade 7. The rearward edges of the washers 18 meet a transverse line at which the tension-spring diverges from the separator-blade and assumes a plane inclined thereto for a portion of its length and thence projects intermediate the separator-blade and the base 14 of folding plate 13, but out of contact with the latter.

A longitudinally movable controlling-member is employed to move tension-spring 16 downwardly into engagement with the lower fabric ply which rests upon the base portion 14 of the folding plate. The controlling-member comprises two sections, a and b. Section a of the controlling-member

is a sheet-metal plate provided with lateral wings or arms 19 bent upwardly to form guide-walls for the shank of section *b* to which is secured a clamping screw 20 which 5 passes through and is movable within a slot formed in section *a* and which serves to permit the adjustment of the sections *a* and *b* relatively to each other. Section *b* of the 10 controlling-member projects through an opening 21 formed in the inclined portion of tension-spring 16 and is provided with a T-shaped head 22 and with an upwardly projecting lug 23, the latter being adapted to slide within a guide-slot 24 formed in the 15 separator-blade 7. It will be seen that movement of the controlling-member in one direction will cause the T-shaped head of section *b* to engage the inclined portion of tension-spring 16 whereby the latter is pressed 20 downwardly into engagement with the fabric, and that movement of the controlling-member in the opposite direction will release the tension-spring. The aforesaid movements are effected by means of a cam-lever 25, the cam portion 25* of which receives the 25 shank of a stud-screw 26 which passes through a slot 27 formed in the forward end of the section *a* of the controlling-member, and is secured to separator-blade 7. The 30 controlling-member is normally held in ineffective position by means of a coiled-spring 28 interposed between the angular end 29 of separator-blade 7 and the angular end 30 of the controlling-member.

35 It will be seen that the controlling-member may be moved into effective position or released for movement into neutral position by manipulation of the cam-lever 25, whereby the tension-spring is moved into and out 40 of its normal position for the purposes described. It will also be seen that the adjustment of section *b* of the controlling-member relatively to section *a* thereof will increase or decrease the wedge action of the member 45 upon the tension-spring 16.

While the improvements are shown in connection with a specific form of hemming and folding attachment, it will be understood that the invention is not limited to 50 such use, and that various modifications may be made in construction and arrangement of the parts without departing from the spirit of the invention.

Having thus set forth the nature of the 55 invention, what I claim herein is:—

1. In hemming and folding attachments

Copies of this patent may be obtained for five cents each, by addressing the "Commissioner of Patents, Washington, D. C."

for sewing machines, the combination with means for folding a fabric, of a separator-blade over which the fabric is folded, a flat tension-spring carried by said separator-blade and adapted to act upon, and normally retracted out of engagement with, one ply only of the fabric, a longitudinally movable controlling-member adapted to hold the tension-spring into engagement with the fabric, and means for manually operating said controlling-member.

2. In hemming and folding attachments for sewing machines, the combination with means for folding a fabric, of a separator-blade over which the fabric is folded, a flat tension-spring carried by said separator-blade and adapted to engage one ply only of the fabric, and manually operable means for controlling the stress of said spring whereby 75 a desired tension may be applied to the fabric.

3. In hemming and folding attachments for sewing machines, the combination with means for folding a fabric, of a separator-blade over which the fabric is folded, a flat tension-spring normally retracted from the fabric and provided with an inclined face adjacent the separator-blade, a controlling-member movable intermediate the blade and the tension-spring and into contact with the inclined face of the latter, and operating means for said controlling-member.

4. In hemming and folding attachments for sewing machines, the combination with means for folding a fabric, of a separator-blade over which the fabric is folded, a flat tension-spring adjacent the separator-blade and normally retracted from the fabric, a controlling-member movable intermediate the blade and tension-spring and adapted to press the latter into engagement with the fabric, means for adjusting said controlling-member to vary its action upon the tension-spring, a spring acting upon the controlling-member to hold the same normally in ineffective position, and a cam-lever for moving said controlling member in opposition to its spring.

In testimony whereof, I have signed my name to this specification, in the presence of two subscribing witnesses.

ALEXANDER McARTHUR.
